UNITED STATES PATENT OFFICE

ELMER E. HICKEN, OF COLLINGSWOOD, NEW JERSEY

TENDER

Application filed January 12, 1929. Serial No. 332,209.

My invention relates to locomotive tenders of the cylindrical type.

One object of the present invention is to make a tender of this type with a cast metal bottom frame, to which the cylindrical portion of the tender is secured, and to provide the usual fuel receptacle at the forward end of the tender, making a portion of the end of the tender an integral part of the frame.

A further object of the invention is to make the seams at the points of connection between the sheet metal cylindrical portion and the top and bottom of the tender with the flanges projecting outwards, so that repairs can be made and new rivets applied at the outside of the tender tank.

In the accompanying drawings:

Fig. 1 is a longitudinal sectional view on the line 1—1, Fig. 3, illustrating my improved tender of the cylindrical type;

Fig. 2 is a plan view of the bottom frame of the tender;

Fig. 3 is an end view of the tender;

Fig. 4 is a transverse sectional view on the line 4—4, Fig. 1;

Fig. 5 is a transverse sectional view on the line 5—5, Fig. 1;

Figs. 6 and 7 are views illustrating the outside joints of the cylindrical portion of the tender tank;

Fig. 8 is a view of the forward end of the casting forming the base and illustrating the end extensions; and

Fig. 9 is a sectional view on the line 9—9, Fig. 8.

Referring to the drawings, the bottom frame 1 of the tender is clearly shown in plan view, Fig. 2, made as a unitary structure, preferably of cast steel. There is an upper plate 2 and a lower plate 3, spaced apart as clearly shown in Fig. 1 and forming a hollow beam, the plates being connected by side members 4. The upper plate 2 is extended at each side as shown in Fig. 4, and forms the bottom of both the fuel section and the water section of the tender. The edges of this upper plate have down-turned flanges 5, and braces 6 extend from the flanged portions of the plate 2 to the bottom plate 3. The centre 50 bearings 7 may form an integral part of the

casting, or they may be made separate as shown in Fig. 1 of the drawings.

Cast integral with the bottom frame are the longitudinal members 8 which form the side walls of a stoker, if one is used. These members have longitudinal rails 9 for the stoker mechanism. At the end of the compartment 10, in which the stoker is located, is a plate 11 also cast integral with the bottom frame 1 and is connected with the side plates 8, as clearly shown in Figs. 1 and 4. This plate has an out-turned flange 12 to which the flange of the inclined plate 13 is attached. This plate forms a division between the rear end of the fuel compartment and the forward end of the water compartment of the tender, and has a vertical portion 13^a which terminates above the water chamber in the present instance.

Cast integral with the plate 8 are ribs 14, to which the transverse dash plates 15 are attached by welding or riveting, and on the inner surface of the end plate 11 are ribs 16 to which the longitudinal plates 17 are attached. In some instances, as shown in Figs. 8 and 9, the end portions 18 are cast integral with the bottom frame and are connected at their inner ends with the longitudinal plates 8, forming the side walls of the stoker chamber 10. When a stoker is not used, the plates 8 form the side walls or a continuation of the fuel compartment.

The side walls of the water compartment A are formed of sheet metal plates 19, curved as shown in Fig. 4. The lower edge of each plate has an outwardly extending flange 20 which is attached to the outwardly projecting flange 5 of the frame preferably by rivets 21 or other fastenings, while the upper edge of the plates have outwardly projecting flanges 22 which are secured to the outwardly projecting flanges 23 of the top plate 24, Figs. 5 and 7, by rivets or other fastenings. By this construction the joints between the side plates and the top plate for the bottom frame can be repaired without discharging the water from the tank and without entering the tank.

The top plate 24 extends from the plate 13^a, separating the water section A from the

fuel section B to the rear header 25, which is flanged at 26. This header is shaped so that it can be secured to the end of the bottom frame 1 above the rear bumper portion 27 of the frame. The forward bumper 28 and the rear bumper 27 are made hollow as shown and extend substantially the full width of the tender, and braces 29 extend from the outer ends of the bumpers to the main frame 10 as shown in Fig. 2, making a very rigid construction.

Cast integral with the bottom frame are ribs 30 in the present instance, to which the transverse dash plates 31 are attached. The 15 side walls of the fuel section B are partly curved to a point where they join the inclined plates 32, separating the forward water compartments from the fuel chamber, and the upper portions 19 of these plates are vertical 20 and the extreme ends are bent in as at 19^b, forming an inwardly projecting flange on each side of the fuel compartment as clearly shown in Fig. 4. Additional braces or dash plates may be used without departing from 25 the main features of my invention, as the number of longitudinal and transverse dash plates depends materially upon the size of the tender.

In the present instance the coupling head 33 forms an integral part of the bottom frame, and in some instances the steps 34 may also be cast integral with the said frame.

By the above construction it will be seen that all seams or joints are on the outside of 35 the water section of the tender, so that access may be had to all the rivets or other fastenings from the outside, dispensing with the necessity for withdrawing the water from the tank section when repairs are necessary, 40 and obviating the necessity of workmen entering the said section; and, as described above, the bottom frame can be made as an integral casting and made with guide-ways for the stoker, when a stoker is used, or the 45 frame may be made with longitudinal walls which form the supports for the partition between the fuel section and the forward end of the water section, and, in some instances, when found desirable, the end portions of 50 the tender may form integral parts of the tender.

I claim:—

1. The combination in a locomotive tender, of a cast metal bottom frame having downwardly projecting flanges at each side; a cylindrical sheet metal tank structure having tank plates with downwardly projecting flanges at their lower edges; and means for attaching said tank plates to the flanges of 55 the bottom frame.

2. The combination in a locomotive tender, of a cast metal bottom frame having downwardly projecting flanges at each side; a cylindrical sheet metal tank structure having side 60 plates with downwardly projecting flanges

at their lower edges; means for attaching said tank plates to the flanges of the bottom frame, said side plates having upper flanges extending downwardly; a top plate having upwardly projecting flanges at each side; and means for attaching said flanges of the top plate to the flanges of the side plates, said top plate forming the top of the water section of the tender. 70

3. The combination in a locomotive tender, of a cast metal bottom frame having integral longitudinal plates forming the lower side walls of the fuel chamber; an integral wall forming an end plate of the fuel chamber; sheet metal plates forming the body of the water section of the tender; and sheet metal plates forming inclined walls separating the fuel chamber from the water chamber. 75

4. The combination in a locomotive tender, of a cast metal bottom frame having integral longitudinal plates forming the lower side walls of the fuel chamber; an integral wall forming an end plate of the fuel chamber; sheet metal plates forming the body of the water section of the tender; and sheet metal plates forming inclined walls separating the fuel chamber from the water chamber, said longitudinal plates and end plate of the fuel chamber having out-turned flanges to which the inclined plates of the fuel chamber are 80 secured. 90

5. The combination in a locomotive tender, of a bottom frame consisting of upper and lower plates and vertical plates forming a central longitudinal tubular member, the upper plate being extended and having down-turned flanges at its edges; sheet metal plates forming the sides of the tender and having down-turned flanges at their lower edges; rivets securing the down-turned flanges of the side plates to the down-turned flanges of the bottom frame, the upper part of the forward portion of said plates being vertical and forming the upper portion of the fuel chamber; inclined plates separating the fuel chamber from the water chamber, said side plates being curved inwardly and having vertical flanges; a top plate with vertical flanges; and rivets securing the flanges of the top plate to the flanges at the upper portions of the side plates. 100 105 110 115

6. The combination in a locomotive tender of the cylindrical type, of an integral cast bottom section extending from one end of the tender to the other and having downwardly turned flanges at each side and cast metal end sections; side plates forming the sides of the tender and having downwardly extending flanges secured to the downwardly projecting flanges of the bottom section; and end plates secured to the cast metal ends of the tender. 120 125
